TURN-COUNTING ADJUSTMENT TOOL

Manuel P. Di Giulio and John H. Rogers, Haverhill, Mass.

Application August 5, 1953, Serial No. 372,530

5 Claims. (Cl. 235—103)

This invention relates to tools for setting rotationally movable adjustment controls, such as the needle valves of carburetors, the tuning controls of electronic equipment and the sights of a gun. The setting of such adjustments generally involves trial and error positioning of the adjustment control through increments of rotation in both directions until the set position is reached, and a determination of the net rotation during any setting of the adjustment control requires accurate measurement of each increment and arithmetical accumulation of the several increments.

The present invention provides an adjusting tool of simple and compact construction for setting rotationally movable adjustment controls while measuring and accumulating the increments of rotation to indicate the direction and amount of the net rotation of the control during any adjustment.

The invention may be embodied in a variety of hand tools commonly used to engage and turn rotationally movable adjustment controls, there being provided a shaft terminating at one end in construction for engaging such controls for rotation coaxial with the shaft, and shaft holding structure secured to the other end of the shaft. Turn counting mechanism operated by the rotation of a rotor is mounted within the shaft holding structure, with the rotor axially aligned with the shaft, and a tenable member that may be held stationary when the shaft and shaft holding structure are rotated, is secured to the rotor. In preferred embodiments the shaft holding structure consists in a handle for the tool, and the tenable member consists of a thimble-shaped cup which, with the handle held between the thumb and middle finger, may be held stationary by insertion of the index finger. Thus, during any adjustment made by the tool of this invention, the turn counting mechanism in the handle is rotated while the rotor is held stationary, and the net rotation is automatically recorded.

This invention will best be understood from the following detailed description of a preferred embodiment thereof, reference being made to the drawings in which:

Fig. 1 is a side view of a screwdriver embodying the invention.

Fig. 2 is a view taken at section 2—2 of Fig. 1, and Fig. 3 is a view taken at 3—3 of Fig. 1.

The screwdriver embodying the invention and shown in the drawings consists in general of a shaft 10 terminating at one end in a screwdriver blade 12, a handle 14 secured to the other end of the shaft, turn counting mechanism 16 mounted in the handle, and a tenable member 18 for operating the turn counting mechanism axially aligned with the shaft and situated at the end of the handle away from the shaft.

The handle 14 is in the form of the hollow cylinder, closed at the shaft end by a plug 20 in which the end of the shaft is firmly embedded, and closed at the other end by a cap 22. The turn counting mechanism 16 consists of a lead screw 24 mounted axially within the handle 14, and an index member 26 threaded to the lead

2

screw. The lead screw 24 is journalled at the shaft end to an inwardly extending boss 28, conveniently formed as an extension to the shaft 10, and is necked down at its other end to form a rotor 30 extending through a central bore 32 in the cap 22.

The index member 26 is conveniently a short cylinder, bearing an index mark 26a on its outer lateral surface, and formed with a key way 34, by which it is keyed to a guide 36 running the length of the handle and secured 10 at its ends in recesses 38 and 40 provided in the plug 20 and cap 22 respectively. The guide 36 is situated behind an elongated window 42 formed in the handle and is imprinted with a scale, registering with the index mark 26a, and calibrated in divisions representing the number 15 of turns made by the lead screw 24. The window is conveniently provided by forming the handle of a transparent plastic coated with an opaque material except at the window.

The tenable member 18 consists of a thimble-shaped 20 cup 44 capping the rotor 30 and secured thereto by a pin 46, and provides a means for holding the lead screw 24 stationary when the screw driver is rotated. Such rotation, it will be seen, is transmitted to the index member 26 through the guide 36 to which it is keyed and 25 causes the index member to travel along the lead screw by an amount corresponding to the direction and degree of rotation of the screw driver. The scale on the guide is preferably calibrated with a central origin, or zero position, and graduated on both sides thereof. 30 Thus, when the mark 26a on the index member is initially set at zero, as by rotation of the tenable member 18, the net rotation and direction thereof during any adjustment may readily be read directly from the scale.

In making such adjustments by the preferred embodiment described above, the handle 14 may easily be grasped between the thumb and middle finger, while the index finger is inserted in the cup of the tenable member 18 to hold it stationary during the adjustment. This has been found to be a particularly natural manual position for 40 work of this type, and is not in the least tiring to the operator.

Although this invention has been described in detail with reference to one preferred embodiment, it will be understood that modifications of the construction may 45 be made without departing from the scope of the invention.

It is contemplated, for instance, that the tenable member 18, may be formed in other shapes adapted for convenient grasping, and that the turn counting mechanism 16 may be modified, for instance, by providing the handle with a longitudinal slot and forming the index member 26 with a pointer radially extending through the slot, to register with a scale situated along the slot and to secure 50 the index member for rotation with the handle. It will be also apparent that this invention may be applied to tools other than screw drivers, for instance socket wrenches, by providing appropriate adjustment control 55 engaging means in place of the screw driver blade 12.

Having thus disclosed our invention and described in detail preferred embodiments thereof, we claim and desire to secure by Letters Patent:

1. In a turn counting adjusting device which includes a shaft terminating at one end in means for engaging an adjustment control for rotation on an axis coaxial with the shaft and a handle secured to the other end of the shaft, the improvement comprising turn counting means including a rotor extending coaxially with the shaft outwardly from the handle and means movable by said 65 rotor indicating relative rotation of the rotor with respect to the handle, and a thimble shaped cup secured at its apex to the end of the rotor, whereby the rotor may be 70

held stationary while the handle is turned and its rotation is indicated.

2. A turn counting adjusting device comprising a shaft terminating at one end in means for engaging an adjustment control for rotation on an axis coaxial with the shaft, a handle secured to the other end of the shaft, a lead screw mounted within the handle in axial alignment with the shaft and terminating in a rotor extending outwardly from the handle, a thimble-shaped cup secured at its apex to the end of the rotor, a scale on the handle, and an index member threaded to the lead screw mounted within the handle for rotation therewith and registering on said scale, whereby turn counting is provided when the handle is turned while the rotor is held against rotation by engagement of the thimble-shaped cup.

3. A turn counting adjusting tool comprising a shaft terminating at one end in means for engaging an adjustment control for rotation on an axis coaxial with the shaft, a handle secured to the other end of the shaft, a lead screw mounted within the handle in axial alignment with the shaft, said lead screw terminating in an external rotor extending outwardly from the handle whereby said rotor may be held stationary when said shaft and handle are rotated, a scale on the handle indicating positions axial of the lead screw, and an index member threaded to the lead screw mounted within the handle for rotation therewith and registering against said scale, whereby turn counting is provided when the handle is turned while the lead screw is held stationary by engagement of said rotor.

4. A turn counting adjusting tool comprising a shaft terminating in means for engaging an adjustment control for rotation on an axis coaxial with the shaft, a handle

connecting with said shaft capable of being grasped to rotate said shaft, and turn counting means including a rotor coaxial with said shaft and having an external portion whereby said rotor may be held against rotation when said shaft and handle are rotated and means movable by said rotor indicating relative rotation of the rotor with respect to the handle and shaft, whereby turn counting is provided when the handle is turned while the rotor is held stationary.

10 5. A turn counting adjusting tool comprising a shaft terminating in means for engaging an adjustment control for rotation on an axis coaxial with the shaft, a handle connecting with said shaft capable of being grasped to rotate said shaft, and turn counting means including a 15 rotor coaxial with said shaft having an external portion whereby said rotor may be held against rotation when said shaft and handle are rotated, and means threaded to said rotor and axially movable with respect thereto indicating relative rotation of the rotor with respect to the handle and shaft, whereby turn counting is provided when the handle is turned while the rotor is held stationary.
